CLAIM

The ornamental breathguard, as shown and described.

DESCRIPTION

FIG. 1 is a right front perspective view of a breathguard; FIG. 2 is a front elevational view thereof; FIG. 3 is a rear view thereof; FIG. 4 is a right side elevational view it being understood that the left side view is a mirror image thereof; FIG. 5 is a top view thereof; FIG. 6 is a bottom view thereof; and, FIG. 7 is a right front perspective view of a second embodiment of a breathguard, the sole difference being the inclusion of the transverse strap member, it being understood that the rear and bottom correspond to that of the first embodiment shown in FIGS. 3-6 and that the opposite side is a mirror image of the side shown.
